UNITED STATES PATENT OFFICE.

ANTON WAGENBACH, OF ELBERFELD, GERMANY.

GRIPPING DEVICE FOR BENDING MACHINES.

Application filed December 7, 1925, Serial No. 73,875, and in Germany August 23, 1924.

For bending iron rods, bending devices are known with motor or hand drive, consisting of a sole plate with a poppet or holder and with a swinging bending lever, holding by bolt the rod which is to be bent. For adjusting the machine to different sizes of the rods and different grades of bending, the bolts can be put into different holes in the bending lever, especially in large bending machines. In smaller bending devices the exact holding of the rods was not possible. In both cases the adjustment was very inexact, so that the wanted curvatures could not be made accurately and relatively long rod ends were wasted because certain length of the rod was wanted for holding the same.

The invention provides a spiral gripping part, which is put onto the bending bolt of the bending lever and can be turned so as to touch by its circumference the rod, to be bent, so that it holds the latter with absolute security at the beginning of the bending by its eccentric circumferential surface in such a way that the rod is pressed against the usual roller, placed in the swinging center of the bending lever. Hereby the rod can be surely fastened at its extreme end without losing a useless piece of rod, and a totally round curvature around the roller is obtainable, as it is wanted, for example, for concrete reinforcing rods. Rods of different sizes can be equally surely fastened in consequence of the great adaptability of the spiral gripping part.

Advantages are obtainable, if two or more spiral gripping parts of different sizes are provided, which can be put onto the bending bolt or, on a roller put on that bolt. By these means it is possible to bend rods of different sizes with only one hole provided for the bending bolt. This design is especially useful for hand-driven bending devices.

The drawing shows the invention in two examples.

Fig. 1 is a top view of the essential parts of a bending machine driven by motor force.

Fig. 2 is a top view of a bending device driven by hand.

Fig. 3 shows a small spiral gripping part of a bending device driven by hand.

In the bending machine according to Fig.

1, on a sole plate 1 a poppet or holder 2 is provided for the rod which is to be bent. Such poppet or holder consists of an abutment and an adjustable eccentric for slidably holding the iron between the parts. Through the plate passes the bending axle 3, which is driven mechanically and carries the bending lever 4 provided with several holes. A roller 5, which fixes the diameter of the hook to be bent, is put onto the end pin of the bending axle 3. A bending bolt 6 is put into one of the holes of the bending lever 4 and onto the said bolt 6 a spiral gripping part 7 is put. The said part 7 before the beginning of the bending process is turned around the bolt 6 in such a way that its circumference is laid exactly against the end 70 of the rod, and during the bending process in the direction shown by the arrow, it is pressed fast, so that the rod is pressed against the roller 5 and bent around it.

The action of the bending device, with 75 hand-drive according to Figs. 2 and 3, is essentially the same with the difference, only, that the pin 3 of the bending lever 4 is a simple fixed pin and the bending lever is moved by hand through a pipe put onto the 80 lever end 8. For bending very thin rods, as shown in Fig. 2, a large spiral gripping part 7^a is used, which is put onto a roller 9, serving also for other purposes and placed onto the bending bolt 6. For thick rods the 85 smaller spiral gripping part 7^b (Fig. 3) can be used, which part immediately fits to the bolt 6. Thereby rods of different sizes can be held without pinning anew the bending bolt. The said bolt can be riveted to its place or made in one piece with the bending lever.

I claim:

1. A gripping device for bending machines, comprising a swingable bending lever, a circular part provided on the swinging center of said bending lever, a bending bolt on said lever, a bending roller on said bending bolt, and a gripping part with a spiral circumference, adapted to be rotatably supported by said roller so as to press a work-piece against said circular part.

2. A gripping device for bending machines, comprising a bending axle, a swingable bending lever on said axle, a freely rotatable roller on said axle, and a freely ro-

tatable gripping part with spiral circumference on said lever, adapted to press a work-piece against said freely rotatable roller.

3. A gripping device for bending machines, comprising a bending axle, a swingable bending lever on said axle, a freely ro-

tatable roller on said axle, a bending bolt on said lever, and a freely rotatable gripping part with spiral circumference on said bolt, adapted to press a work-piece against said freely rotatable roller. 10

In witness whereof I affix my signature.

ANTON WAGENBACH.
